(57) **CLAIM**

The ornamental design for plant light, as shown and described.

DESCRIPTION

FIG. 1 is a perspective view of plant light showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of a portion of FIG. 1;

FIG. 9 is an enlarged view of another portion of FIG. 1;

FIG. 10 is an enlarged view of a portion of FIG. 2;

FIG. 11 is an enlarged view of a portion of FIG. 3; and,

FIG. 12 is an enlarged view of a portion of FIG. 6.

The broken lines in the drawings depict portions of the plant light that form no part of the claimed design. The additional broken lines encircling the enlarged views in FIGS. 1-3, 6, and 8-12 and 10 are for annotative purposes only and form no part of the claim thereof.

1 Claim, 12 Drawing Sheets(56)
